JOHN DEAM KNEEDLER, OF SIOUX CITY, IOWA, ASSIGNOR OF TWO-FIFTHS
TO BUEL COUCH AND ONE-FIFTH TO NELSON T. HANSON, OF SIOUX
CITY, IOWA.

SECURING MEANS FOR TRACK-RAILS.

No. 821,509.

Specification of Letters Patent.

Patented May 22, 1906.

Application filed December 22, 1905. Serial No. 293,012.

To all whom it may concern:

Be it known that I, JOHN DEAM KNEEDLER, a citizen of the United States, residing at Sioux City, in the county of Woodbury and State of Iowa, have invented certain new and useful Improvements in Securing Means for Track-Rails; and I do hereby declare the following to be a full, clear, and exact description of the invention, such as will enable others skilled in the art to which it appertains to make and use the same.

My invention relates to railroad-ties and to means for securing rails thereto; and the object of the invention is to provide simple and durable means whereby rails may be quickly secured to or removed from the ties, said means being also capable of securely fastening the rails in position so as to prevent them from spreading or becoming otherwise accidentally displaced.

The invention consists of bed-blocks formed of artificial stone, each block having a plate embedded within it into which are threaded bolts which extend above the block and through the metallic tie which is mounted on the upper surfaces of and connects two of the blocks. This metallic tie has end shoulders or abutments formed upon it against which are adapted to rest a rail-brace through which one of the bolts extends and is secured by novel means employed by me.

A holding-plate engages the inner base-flange of each rail and is retained by one of the bolts.

The invention also consists of the further novel features of construction and combination of parts, the preferred form whereof will be hereinafter made clearly apparent, and pointed out in the claims.

In the accompanying drawings I have shown the preferred form of my invention.

In said drawings, Figure 1 is a longitudinal section through a tie constructed in accordance with my invention and utilizing my improved rail-securing means, said means and the rails being shown in section. Fig. 2 is a plan view of the parts shown in Fig. 1. Fig. 3 is an enlarged elevation of the upper portion of one of the bolts. Fig. 4 is an enlarged section through the upper portion of a bolt and showing a modified means for securing the rail-holding plate upon the bolt.

Fig. 5 is a plan view of a washer used in connection with the securing means shown in Fig. 4, and Fig. 6 is a section through one end of a tie and showing another modified means for fastening a rail in position.

Referring to the figures by numerals of reference, 11 are artificial-stone bed-blocks of any desired contour and proportions, and embedded within each of these blocks is a longitudinally-disposed plate 2, having threaded apertures therein which are engaged by the threaded ends of bolts 3, which extend upward from the blocks and are adapted to project through apertures 4, formed in a metallic strip 5, which is mounted on the two bed-blocks 1 and constitutes a metallic tie. An end plate or abutment 6 is riveted or otherwise secured to the tie 5 at each end thereof and constitutes an abutment for a rail-brace 7, in the form of a plate which fits snugly upon the outer base-flange of a rail 8 and against the web and the lower surface of the head of said rail. Each of these brace-plates has an opening through which one of the bolts 3 extends, and the upperend of the bolt is slotted longitudinally, as shown at 9, to receive a key-pin 10, which is disposed above an angular washer 11. A suitable washer 12 is interposed between this washer and the rail-brace, so as to prevent the rotation of the washer. The inner base-flange of each rail is engaged by a holding-plate 13, through which one of the bolts 3 extends, said bolt being preferably provided with securing means such as described in connection with the bolt extending through the brace-plate.

While I preferably employ the construction described in fastening the plates 7 and 13 to the tie, I can, if desired, groove the bolt, as shown at 14 in Fig. 4, and instead of inserting a key-pin through a slot in the bolt can extend a key 15 down into groove 14 and into grooves 16, formed within the washer 17, nut-lock 18, and tie 19. Still another construction can be utilized for fastening the plates 13 upon the rails, such a construction being disclosed in Fig. 6, wherein one of the bolts 3 is formed with a laterally-extending head or tongue 20, which takes the place of the securing-plate 13 and overlaps the inner base-flange of the rail. A washer 21 is preferably interposed between this head 20 and the tie.

5. Where any of the constructions herein described are utilized, the rail can be easily released by knocking the plate 13 or the head 20, as the case may be, to one side, thereby forcing it off of the inner base-flange and permitting the rail to be slid from under the brace-plate 7. The head 20 and the securing-plate 13, however, engage the rail with sufficient pressure to prevent them from being accidentally disengaged therefrom.

What I claim is—

1. The combination with bed-blocks and metallic plates embedded therein; of bolts adjustably engaging the plates and extending from the blocks, a tie uniting said blocks and engaged by said bolts, abutments at each end of said tie and secured thereto, braces interposed between said abutments and the outside of the rails, and movable means upon the tie for engaging the rails and holding them against the braces.

2. The combination with a bed-block and a plate embedded therein; of bolts engaging the plate and extending from the block, a tie mounted on the block and engaged by the bolts, said tie having an abutment thereon, a rail-brace upon the tie and against the abutment, said brace being engaged by one of the bolts, means upon said bolt for clamping the

rail-brace upon the tie, and movable means upon the other bolt for engaging the rail and holding it upon the brace.

3. The combination with a bed-block and a plate embedded therein; of bolts threaded into the plate and extending from the block, a tie upon the block and engaged by the bolts, a rail-brace upon the tie engaged by one of the bolts, adjustable means upon said bolt for clamping the brace upon the tie, and laterally-movable means upon the other bolt for engaging a rail and holding it in engagement with the brace.

4. The combination with bed-blocks and metallic plates embedded therein; of a tie uniting said blocks, bolts adjustably engaging said plates and tie, rail-braces upon the outer bolts, means carried by said tie and rigidly secured thereto to reinforce said braces, and laterally-movable holding-plates for engaging the inner side of the rails and holding them against the braces.

In testimony whereof I have signed my name to this specification in the presence of two subscribing witnesses.

JOHN DEAM KNEEDLER.
